Attorney

UNITED STATES PATENT OFFICE.

RALPH W. HARRIS, OF CRANFORD, NEW JERSEY.

HEADLIGHT.

Application filed May 9, 1922. Serial No. 359,533.

To all whom it may concern:

Be it known that I, RALPH W. HARRIS, a citizen of the United States, residing at Cranford, in the county of Union and State of New Jersey, have invented a new and useful Headlight, of which the following is a specification.

This invention relates to head lamps and more particularly to head lamps especially designed for use on motor vehicle or the like.

The primary object of the invention is to provide novel means for deflecting the light rays projected from the lamp, to eliminate blinding of persons moving towards the lamp.

Another object of the invention is to provide novel means for adjusting the lamp with respect to the body portion or reflectors thereof to facilitate the focusing of the lamp.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a sectional view through a head lamp constructed in accordance with the present invention.

Figure 2 is a sectional view taken on line 2-2 of Figure 3, portions of the lamp structure being removed.

Figure 3 is an enlarged detail view of the lamp supporting means.

Figure 4 is a sectional view taken on line 4-4 of Figure 3.

Figure 5 is a side elevational view of the plug forming a part of the invention.

Figure 6 is a longitudinal sectional view through the plug.

Figure 7 is an end view thereof.

Referring to the drawings in detail, the reference character 5 designates the body portion of the lamp casing, which is of the usual construction, the same being formed with a flange 6 providing a support for the lens 7.

Positioned within the casing 5 is a reflec-

tor 8, which is also curved to conform to the curvature of the lamp casing, the reflector being however spaced from the inner surface of the casing 5. The lamp support includes a tubular body portion 9 through which the wires 10 extend, which wires have connection with a suitable source of electric supply not shown, for supplying electric current to the rods 11, which provide the support for the reflector 12 and bulb 13.

Positioned on the rods 11 is a fibre bar 14 designed to insulate the socket member 15 from the rods 11 to prevent short circuiting. This socket member is secured to the bar 14 as by means of the screw 16, which socket member also has connection with the reflector 12 that has its concaved surface facing the concaved surface of the reflector 8, so that the light rays projected from the lamp 13 supported by the socket member 15 will be reflected onto the reflector 8.

A contact member 19 is secured to the bar 14 and has one end thereof contacting with one of the rods 11, while the opposite end of the contact member engages the socket member 15.

The contact member 20 is also supported on the bar 14 and has its inner end engaging the contact end 21 of the socket member 15, the opposite end of the contact member being curved and contacting with the opposite rod 11 completing the circuit to the socket 15, and lamps supported thereby.

It might be further stated that the connection between the bar 14 and rods 11, is such as to create a binding action therebetween, causing the bar 14 to be frictionally held in various positions of adjustment along the rods 11.

The reflector 12 is formed with openings at points adjacent to the periphery thereof, which openings accommodate the rods 11, a suitable insulating material 28 being positioned in the openings, to insulate the reflector 12 from the rods.

Thus it will be seen that by moving the bar 14 and lamp supported thereby, towards and away from the main reflector 8, the lamp may be properly focused. The outer ends of the rods 11 are connected as by means of the fibrous bar 22, as clearly shown by Figure 1 of the drawings. It is contemplated to provide a lamp supporting structure which may be readily and easily positioned in the usual lamp sockets so that the rods 11 will be dis-

posed in horizontal parallel relation with each other, and to this end, I have provided a novel form of adjustable plug.

This plug is indicated at 23 and is formed 5 with a recessed portion to accommodate the sleeve 24 that carries the laterally extending pins 24' that move in the usual bayonet slots of a lamp socket. As shown, the ends of the 10 rods 11 extend into the plug 23, the end of one rod extending beyond one end of the plug 23, where the same extends at right angles to provide a contact member 25. A lock washer 26 is positioned over one end of the 15 plug, and held thereon by means of screws 29 and engages the sleeve 24 to hold the same in its adjusted position, there being provided a lug 27 on the washer 26 that contacts with the under surface of the member 25 to set up a binding action between the 20 washer and sleeve 24.

From the foregoing it will be seen that should it be desired to move the pins 24' to permit the bars 11 to be supported in horizontal parallel relation with each other, the 25 washer 26 may be removed and the sleeve 24 rotated on the plug to bring the pins in proper relation with the bayonet openings in which the plug is positioned. The washer 26 is now replaced to hold the collar in such 30 adjusted position.

Having thus described the invention, what is claimed as new is:—

1. In a device of the character described, a lamp casing, a reflector supported within 35 the lamp casing, a lamp supporting member including rods disposed in parallel relation with each other, an insulating bar movable on the rods and carrying a lamp socket, means contacting with the rods for supplying electric current to the lamp socket, and said insulating bar adapted to be adjusted along the rods to adjust the lamp supported thereby, with respect to the reflector.

2. In a device of the character described, 45 a lamp casing, a reflector within the lamp casing, supporting rods within the lamp casing, an insulating bar connecting the rods,

said insulating bar adapted to be moved longitudinally of the rods, a bulb and reflector supported by the bar, means carried by the bar for completing a circuit to the 50 lamp, and said bar adapted to be moved longitudinally of the rod to adjust the same with respect to the first mentioned reflector.

3. In a device of the character described, a lamp casing, said casing having a central 55 plug opening, a reflector within the casing, supporting rods, an adjustable lamp supporting means movable on the rods, a lamp and reflector mounted on the adjustable lamp supporting means, an adjustable plug, said rods 60 having their ends disposed within the adjustable plug, and said plug adapted to be positioned within the socket member.

4. In a device of the character described, a lamp casing, supporting rods positioned 65 within the casing, a plug connecting the inner ends of the supporting rod, an adjustable lamp supporting member movable throughout the lengths of the rods, a reflector within the casing, a reflector positioned on the lamp supporting member and having its convexed surface disposed opposite to the convexed surface of the main reflector a lamp carried by the lamp supporting member and electrical means carried by 70 the adjustable lamp supporting member for 75 supplying electrical current.

5. In a device of the character described, a lamp casing, a pair of spaced supporting rods mounted within the casing, a stationary bar for connecting the outer ends of the supporting rods, a movable bar positioned on the rods and carrying a reflector, curved contact members on the movable bar and engaging the supporting rods to receive electric current therefrom, and said movable bar adapted to be moved with respect to the 80 stationary bar.

In testimony that I claim the foregoing as my own I have hereto affixed my signature.

RALPH W. HARRIS.
